UNITED STATES PATENT OFFICE.

WILLIS H. SARGENT, OF ST. JOHNSBURY, VERMONT, ASSIGNOR TO THE
E. & T. FAIRBANKS & CO., OF ST. JOHNSBURY, VERMONT, A CORPO-
RATION OF VERMONT.

DESIGN FOR A SCALE-BEAM SUPPORT.

SPECIFICATION forming part of Design No. 35,969, dated July 1, 1902.

Application filed May 12, 1902. Serial No. 107,045. Term of patent 7 years.

To all whom it may concern:

Be it known that I, WILLIS H. SARGENT, a citizen of the United States, residing at St. Johnsbury, in the county of Caledonia, State of Vermont, have invented a certain new and original and ornamental Design for a Scale-Beam Support, of which the following is a description, reference being had to the accompanying drawing, and to the letters of reference marked thereon.

My invention relates to a new and original design for a scale-beam support; and it consists in a scale-beam support of the shape and configuration shown and having the ornamentation hereinafter described embodied therein.

My invention is illustrated in the drawing, in which the figure represents an elevation of a scale-beam support embodying my design.

In the drawing the base-pieces are shown at A A'. The direct beam-supports B B are formed upon the upper ends of curved arms C C, which extend from the supports B B downwardly in curved lines and form a scroll or spiral, the hub or inner part of the spiral shown at D D being enlarged.

E represents a panel to which the scroll is attached and above which portions of it F F of the scroll extend, this panel being ornamented with the representation of an eagle 30 with outstretched wings holding in his beak and beneath his claws a serpent and resting with his feet upon the representation of a cactus-plant. A portion of the scroll is hidden by the outstretched wings of the eagle. 35

The leading feature of the design consists of a scale-beam support having the scroll arrangement of supporting-arms and embodying the panel with the ornamentation thereon.

Having thus described my invention, what 40 I claim, and desire to secure by Letters Patent, is—

The ornamental design for a scale-beam support; substantially as shown and described. 45

In testimony whereof I affix my signature in presence of two witnesses.

WILLIS H. SARGENT.
